UNITED STATES PATENT OFFICE.

ALBERT SCHEIBLE, OF CHICAGO, ILLINOIS.

SPRING-BED.

1,053,229.

Specification of Letters Patent. Patented Feb. 18, 1913.

Application filed April 22, 1912. Serial No. 692,323.

To all whom it may concern:

Be it known that I, ALBERT SCHEIBLE, a citizen of the United States, residing at Chicago, in the county of Cook and State of Illinois, have invented a new and useful Spring-Bed, of which the following is a clear, concise, and full specification, reference being had to the accompanying drawings, forming part of this application.

10 My invention relates to spring beds and consists in a novel construction whereby the springs may be more economically packed and stored without danger of damaging the springs; also whereby the bed-bottom may 15 be lowered without shortening the effective length of the springs. I attain these objects by the construction shown in the accompanying drawings, in which—

Figure 1 is an elevation of part of an 20 end of the bed-bottom and slat, and of the parts attached to the same, a portion of the guard formation being cut away to avoid confusion. Fig. 2 is a vertical section through the same along the line 2—2. Fig. 25 3 is a plan view of the central portion of Fig. 1. Fig. 4 is an end view of the slat end and bed-bottom end.

In the drawings, A A are end portions of the resilient bed-bottom which is preferably 30 made of latticed strips A' terminating in the helical springs shown in the drawings.

B B are vertical perforations in the end-piece C of the bed-bottom frame. When the springs A are hooked into these perforations B B, the end portions A'' project vertically above the top of the end-piece C.

D is a slat, preferably of angle steel, placed directly under the end-piece C.

E is a spring interposed between the slat 40 D and the end-piece C, this spring being preferably fastened at its ends by rivets F and F'. G is the adjacent side-rail of the bedstead.

H is a hanger, preferably of malleable 45 iron, pivoted to the slat D close to its end by means of a pin I. The hanger H has one end H² adapted to rest upon the top of the side rail G, thereby supporting the slat D when in its normal or operative position.

50 K is a latching member having one end attached to the hanger H, while its other end normally slips into a socket L in the slat, thereby preventing the hanger H from moving upon its pivot I.

55 When the spring is to be stored or

shipped, the latching member K is changed from the socket L to another socket M, thereby swinging the hanger H to the position H', in which position the upper end of H' engages the lower edge of the end-piece 60 C of the bed-bottom frame. To make this engagement all the more firm, I preferably form a flat surface H² on the upper end of the hanger H, the distance between this flat surface and the pivot I being such that the 65 spring E will have to be slightly distended when the hanger is moved into the position H'. By thus springing the slat D and the end-piece C slightly out of their normal distance from each other, I cause the spring E 70 to draw the end-piece C tightly against the tip of the hanger H', thereby giving an additional means for holding this in the wedged position in which it acts as a brace or stiffening member. When the hangers 75 at the ends of each slat are swung into these wedged positions and latched in the same by the latches K, the ends of the hangers which normally engage the side-rails of the bed no longer project from the framework of the 80 bed-spring, so that this may be more easily packed and may be handled without danger of breaking off the projecting tips. Having thus safeguarded the hangers, I also protect the spring E from injury in transit by 85 means of a guard N attached to the end-piece C and preferably having parallel legs N' and N² joined by a portion N³ passing below the bottom of the slat D. This joining portion or foot N³ is preferably made a 90 little narrower than the distance between adjacent spring ends A of the bed-bottom, so that when two bed springs of my construction are placed upon one another, the feet N³ of the upper bed spring will slip between the vertical portions of the spring 95 ends A on the lower one and will be engaged by them to prevent the upper bed spring from sliding crosswise upon the lower. Moreover, the weight of the bed-bottom and of any additional bed springs piled upon the same will be borne by the guards N which relieve the springs E of all 100 weight when the bed springs are thus stored. Hence any desired number of such bed 105 springs may be piled upon one another without damaging the auxiliary springs E used between the slats and the bed-bottoms. When the hanger is drawn back into the 110 position H' and latched in this position by

the latch K, the hanger serves as a brace between the slat and the bed-bottom, thereby making a rigid structure out of the spring and slat formation. Hence the bed-spring as a whole can easily be stored and transported without injury and without the need of costly crating or boxing.

While I have shown and described my invention as embodied in a form having a latticed bed-bottom and vertically coiled auxiliary springs, I do not wish to be limited to these, it being obvious that many modifications could be made in the form and arrangement of the parts without departing from the spirit of my invention.

What I claim as new and desire to cover by Letters Patent is:

1. A bed construction, including a resilient bed-bottom; a slat; a spring interposed between the slat and the bed-bottom; a bedstead having side-rails; and a movable hanger for suspending the slat below the side-rail and transversely of the latter, the projecting end of the hanger being adapted to be withdrawn when the bed spring is not in use.

2. A bed construction; including a resilient bed-bottom; a slat; a spring interposed between the slat and the bed-bottom; and a guard for protecting the spring from mechanical injury.

3. A bed construction, including a resilient bed-bottom; a slat; a spring interposed between the slat and the bed-bottom; and a guard for protecting the spring from mechanical injury, the guard being attached to the bed-bottom and projecting below the

slat to serve as a foot for the bed-bottom when not supported by the slat.

4. A bed construction, including a resilient bed-bottom; a slat; a spring interposed between the slat and the bed-bottom; and a foot attached to the bed-bottom; the feet upon one such bed spring being adapted to slip between raised portions upon the upper surface of the bed-bottom of a similar bed spring placed beneath the same.

5. A bed construction, including a resilient bed-bottom and a slat; a spring interposed between the slat and the bed-bottom; a bedstead having side-rails; and a movable hanger fastened to an end of the slat; the hanger serving in one position for suspending the slat below the side-rail transversely of the latter, and in another position as a brace between the slat and the bed-bottom.

6. A bed construction, including a resilient bed-bottom and a slat; a spring interposed between the slat and the bed-bottom; a bedstead having side-rails; and a movable member fastened to the slat and serving, when the bed spring is in use, as a foot by which the slat is stepped upon the side-rail of the bedstead; the said member being movable into engagement with the bed-bottom, whereby it may serve as a brace to prevent an overstraining of the spring when the bed construction is not in service on a bedstead.

ALBERT SCHEIBLE.
